UNITED STATES PATENT OFFICE

ALBERT JAHN, OF BERLIN-LICHTERFELDE, GERMANY

FOUNTAIN PEN

Application filed September 22, 1928, Serial No. 307,627, and in Germany April 28, 1928.

This invention relates to a fountain pen with a body of non-circular cross section and with extensions of circular cross-section at the ends for the accommodation of the nib and cap respectively, improved in that the surface of said body is composed of a longitudinal flat face serving as support for the index finger and of a curved surface symmetrically arranged with regard to the longitudinal bore. This body is positioned in relation to the tubular front extension so that the symmetry plane of the feeder which coincides with that of the nib divides the body into two unequal parts and that the plane of the lower edges of the nib forms with the flat face of the body an acute angle amounting to more or less exactly 45°.

This arrangement has for its object to provide a pen which is well-balanced, has a gripping portion without threads, and a surface for the index finger without convexity, and when the nib in writing position is put on the paper, simultaneously the flat side of the body is presented automatically in most comfortable position for the index finger in that it offers a suitable incline for said index finger and requires the least exertion from the acting muscles so that none of them undergo any strain and no fatigue or cramp will occur, whereby the writing will be more regular.

Further, the pen cannot roll if placed on inclined planes and also the ink cannot work its way from the tube at the front end onto the body.

So as to adapt the body to the round end portions, said body may be tapered at each end and preferably carries a collar at each end of ring or segmental shape according to the cross section of the body.

The tubular extension for the accommodation of the nib and feeder placed at the front end of the body, forms a rigid unit with the body in the case of safety pens whereas for autofill pens it is divided into a rigid part with threads and a movable part, the end of which is inserted into said rigid part. The cap which, when the pen is in use, reposes on the rear extension may be placed over this front tubular extension in order to protect the

nib when the pen is not in use. The nib is inserted in this tubular extension and arranged so that the plane of the lower edges of the nib forms an acute angle preferably of about 45° with the flat face of the body, and that the symmetry plane of the feeder symmetrically fixed to the nib divides the body into 2 unequal parts.

The short rear end extension of the body, adapted for attaching the cap, forms one piece with the body in the case of autofill pens whereas for safety fountain pens it is composed in the known way of a rigid cylindrical portion and a rotatable conical portion. This rear extension of the body combined with the cap serves as shaft for the pen holder.

It may be concentric or eccentric to the body, but is preferably slightly displaced, the centre of its cross section being arranged either in the symmetry plane of the body equally distanced from the curved and straight portions of the contour or outside of the symmetry plane towards the face gripped by the thumb, so that the cross section of the rear extension is divided by the symmetry plane of the body into 2 unequal portions.

The latter form relates only to autofill fountain pens and requires a small additional flat face on the body to facilitate the merging from the body portion into the cylindrical extension.

Several forms of construction of the fountain pen holder are shown in the accompanying drawing.

Fig. 1 shows in front elevation the fountain pen ready for use.

Fig. 2 shows the fountain pen shown in Fig. 1 viewed in the plane of the surface for the index finger.

Fig. 3 is a side elevation of Fig. 2 the index finger surface turned to the left through an angle of 90° and the cap separate from the shaft.

Fig. 4 is a front end view of Fig. 1.

Fig. 5 is a rear end view of the fountain pen, the cap being removed.

Figs. 6 to 16 show similar views as Figs. 1 to 5 of an autofill fountain pen with the shaft extension displaced towards the side.

resting surface for the thumb with regard to the central axis of the body.

Fig. 11 shows the holder gripped by the fingers in position for use.

- 6 Referring to Figs. 1 to 5, the fountain pen comprises a non-circular thick body 1 tapering towards the ends 3 and 4 and having a flat surface 2 and a curved surface. A tube is composed of a rigid part 5" and a part 10 5' inserted in the rigid part 5", the extension of the front end of the body 1, the nib 6 and the feeder 6' being arranged in the part 5' so that the symmetry plane of the feeder coincides with that of the nib and that the 15 nib with the plane of its lower edges forms an angle of about 45° with the plane surface 2 of the body. Between the part 5" and the body a collar 3' is arranged. The part 5" is further designed to hold the cap for protecting the nib. The shaft consists of a cylindrical extension 8 and is designed to hold the cap 7.
- 20 The shaft extension 8 is slightly displaced towards the vertex with regard to the central axis of the body.

The fountain pen shown in Figs. 6 to 10 has the rear extension 8 slightly displaced towards the side for the thumb with regard to the body so that the circular cross section of this extension touches approximately the chord 2 and the arc of the cross section of the body. The body 1 has at its rear end an indentation 11 extending downwardly in spiral shape tangentially from the base 35 of the extension to the flat surface 2 of the body. This indentation is designed to facilitate the pressure of the shaft against the hand.

I claim:

- 40 1. In a fountain pen with a body of non-circular cross section, formed by a longitudinal flat face serving as support for the index finger, and by a curved face symmetrically arranged with regard to the longitudinal bore and with extensions of circular cross section at the ends for the accommodation of the nib and cap respectively, the combination of said body with the feeder symmetrically arranged to the nib and positioned in the front tube in such a manner, that the symmetry plane of the feeder divides the handle into two unequal parts.

45 2. A fountain pen as claimed in claim 1, characterized in that the plane of the lower edges of the nib forms an acute angle of about 45° with the flat face of the handle portion.

50 3. A fountain pen as claimed in claim 1, characterized in that the rear end extension of the handle portion is concentric to the central axis of the handle.

55 4. A fountain pen as claimed in claim 1, characterized in that the rear end extension of the handle portion is displaced with regard to central axis of the handle towards

the longitudinal bisecting line of the curved surface of the handle.

5. A fountain pen as claimed in claim 1, characterized in that the extension at the rear end of the handle portion is displaced with regard to the central axis of the handle portion towards the side for the thumb.

6. A fountain pen as claimed in claim 1, characterized in that the tubular front extension of the handle portion is composed of a part rigid with the handle having an external thread and of a movable part inserted into the rigid part and holding the nib and feeder.

In testimony whereof I affix my signature. cc
ALBERT JAHN.
